CONTINUOUS VENTILATOR

Abraham Herman and Joseph Herman,
Los Angeles, Calif.

Application December 5, 1939, Serial No. 307,620

11 Claims. (Cl. 98—42)

Our invention relates to a type of ventilator designated in the art as continuous in that a plurality of ventilator dampers are arranged in a row or sequence and usually raised and lowered as to a single elongated damper or a group of dampers. This type of overhead ventilation is usually built on a roof and sometimes at the ridge of the roof.

This type of continuous ventilator with dampers in which relatively large vertical openings in a roof or similar structure are controlled by dampers which raise and lower and thus increase or decrease the distance between the damper and the periphery of the ventilating openings require baffle or louver structures to prevent rain and snow blowing directly into the building underneath the damper and also to eliminate down-drafts but at the same time provide a sufficient space for the updraft of the heated and contaminated air from the building.

Many attempts and various constructions have been designed, patented and used in actual constructions to raise and lower the continuous type of dampers but many of these have numerous defects such as being quite complicated as to the particular mechanism employed, others use a system of levers and links, some of these operating on the toggle principle. Again, others have one or more cables extending longitudinally of the series of dampers which by a system of levers or lift rods or posts elevate the damper or dampers. Further, in some of the types of damper operating mechanism it is necessary to have the devices which are manipulated by hand or by power located below the dampers and spaced along the building. This frequently requires so many of the manipulating structures that they interfere with machines and other equipment installed in the building underneath or adjacent the dampers.

A main object and characteristic of our invention is the provision of a cable lift for a single elongated damper and thus for the series of dampers extending longitudinally of the roof and forming what is designated in the trade as a continuous ventilator. A further feature of our invention resides in providing cables spaced longitudinally of a damper and preferably connected alternately on opposite sides of the center or ridge of the damper. Thus as the cables lift or lower the damper, it is maintained in an even, that is, its proper horizontal position although increasing or decreasing the vertical distance between the damper and the structure having the ventilating opening.

Another characteristic and feature of our invention to facilitate operating all of the cables simultaneously is in the provision of a longitudinally extending central shaft or elongated cable drum or winch, each of the series of cables connected to such shaft being spaced longitudinally thereof, hence as the shaft is rotated in one direction, all of the cables connected to such shaft and to a particular damper are wound in and thus elevate the damper, this being done in such a manner as to prevent the damper from tilting sidewise or from having one end rise faster than the other end. Manifestly in the reverse rotation of the shaft the damper or dampers are lowered. In our invention the shaft may be connected to raise and lower a series of dampers at one time.

As in this type of damper control there are many and manifest advantages of manual operation, a further feature of our invention relates to the mechanism for rotating the shaft, this comprising an elevated gear system with a driving gear operated by a depending chain having two drop lengths, one for elevating the damper and the other for retracting these downwardly. By a suitable gear transmission connected to the chain pulley, the longitudinal shaft may be rotated in one direction or another.

As it is highly desirable to have a reliable damper closure operating in case of fire, our invention further comprehends equipment for automatically closing the series of dampers, this being released by a fusible link or similar device or devices when the temperature in the building reaches a pre-determined degree for a sufficient length of time. In view of the fact that the shaft for reeling the lift cables is in an elevated position and the cables for a manual manipulation extend downwardly into the building, we employ a weight released on the fusing of a link or equivalent device to actuate the chain giving the downward movement to the dampers. As these dampers are of considerable weight, it is

desirable to have a counterweight on the chain used to raise the dampers to substantially balance the same. This makes the manual operation of opening and closing the dampers easier and further, the fire released dropweight is such as to overbalance the counterweight, start the shaft rotating in the direction to unwind the cables and to continue this movement until the cables are unwound sufficiently to completely lower the dampers to the closed position as to the ventilation openings.

Our invention is illustrated in connection with the accompanying drawings, in which:

Fig. 1 is a vertical transverse section through a ventilator taken on the section line 1—1 of Fig. 2 in the direction of the arrows.

Fig. 2 is a partial section with certain interior portions being shown in elevation through the ventilator illustrating particularly the lifting mechanism for the damper.

Fig. 3 is a detail vertical section on the line 3—3 of Fig. 2 in the direction of the arrows.

In using the continuous ventilator and damper of our construction it is obvious that the inventive features of the damper as to its raising and lowering construction may be used with many types of roof and general ventilator assemblies. In the type of supporting and ventilating structure the roof or the other portion of a building to be ventilated by overhead ventilation is provided with a series of spaced transverse bar members 11 illustrated as having a central horizontal section 12. A sheet metal rain runoff covering 13 is secured to this structure and illustrated as having opposite vertical walls 14, a horizontal shoulder 15 and vertical rim 16. A net or wire screening 17 is stretched across the opening between the side walls 14 being supported on the shoulder 15. Also spaced longitudinally of the building there are upright frame members 20 which may have a suitable contour and form the support for lateral sheet metal covering 21, this being carried sufficiently high to deflect the wind blowing across the roof and having sufficient opening at the bottom for drainage of water, the blowing out of snow or the drainage of water from melted snow. Connected to the supports 20 we provide the top framing construction 25 which is illustrated as having bar members 26 connected to the vertical supports 20, sloping members 27 and a horizontal top section 28. Also spaced longitudinally of the roof construction there is a lower and secondary system of braces 30 having horizontal brace bars 31. The deflecting apex 35 formed of sheet metal gives a coverage over these frames 25 and 30 and a sufficient housing extending beyond the width of the damper.

Other non-moving and structural members include a series of vertical posts 40, these being in the form of rods which are round in cross section and secured by an upper and lower threaded bolt connection 41 to the horizontal section 12 of the cross bar assembly 11. These at their upper end have a head 42 into which they are threaded and this being secured to a U-shaped bearing center 43 of the horizontal cross member 28. There are additional and shorter vertical supporting posts or rods 45 secured in a similar or any suitable manner to the cross bars 12 shown in detail in Fig. 2, these extending upwardly and are secured in a threaded head 46 attached to and depending from the cross bar 31, the purpose of this additional and lower support being defined hereunder.

The continuous damper 50 has a sheet metal top 51, two opposite downwardly extending skirts 52, the damper terminating at a transverse end 53 and having a rectangular opening 54 usually at approximately the center of the damper for purposes hereunder defined. Tapering sleeves 55 surround and ride on certain of the supporting posts 40. As such necks engage the top of the damper adjacent a circular opening, these dampers usually have sufficient transverse stiffness and are made long in proportion to the width

usually arranged in rows and thus being designated continuous dampers.

The immediate lifting and lowering equipment designated by the assembly numeral 65 comprises a longitudinal shaft 66, this being made tubular for sake of lightness. These shafts are supported in the journal 43 as illustrated in Fig. 3 merely resting in the U-shaped journal and may be of any desired length. It is preferable that the shaft be of sufficient length to operate one complete damper although it may be much longer and used to lift two or more dampers. The hollow shafts are connected to driven shafts 67 which are preferably solid cylindrical shafts fitted therein and driven by a gear system hereunder described. The lifting cables 70 have upper ends 71 secured to the hollow shaft 66 in spaced relation as shown in Fig. 2 and preferably have a drop section 72 which have a slope considered in a longitudinal direction and also outwardly as shown in Fig. 2 and are connected with the lower ends connected to the eyes 73 in the damper 51, these eyes being staggered and spaced apart on opposite sides of the center. The purpose of having the cables staggered and spaced apart and with the slope as to the longitudinal center is that the winch coil 74 as the cables wind on the shaft will not cause the over-ride of the cable on the turns or convolutions already wound on the shaft. Thus in rotating the shaft for winding in the cables these have a substantially even spacing longitudinal of the shaft without any over-ride and thus develop an even up-pull and drop for the damper. Thus an individual damper is raised and lowered without any lateral tilt, both of the drop sections on opposite sides of the longitudinal center being evenly lifted and all of the cables from one end to the other of a damper being raised and lowered equal distances in accordance with the rotation of the shaft 66.

The power gear train equipment to rotate the shaft 66 designated by the assembly numeral 85 utilizes a chain pulley 86 located in a housing 87 and supported by a bracket 88 connected to the cross bar 28 and having an upper journal clamp 89. A chain 90 operates over the pulley and has a pull end drop section 91 with a certain number of large links 92 adjacent the end. The counterweight section 93 has a counterweight 94 mounted thereon, this counterweight being approximately sufficient to balance the weight of the damper when it is lifted by the cables. The pulley has a bevel gear 95 connected thereto or formed integral therewith and such bevel gear drives a complementary bevel gear 96 at right angles thereto, this latter being splined or otherwise secured to the short shafts such as stub shafts 67 which are connected to the tubular shaft 66, hence by this construction when the pull end of the chain 91 is pulled downwardly, the chain pulley is rotated, thus rotating the gear system and the shaft assembly 67 and 66 to raise the dampers such as from the closed and full line position of Fig. 1 to the full open and dotted position of such figure and as above mentioned, the counterweight 94 substantially balances the damper and thus retains it at any desired elevation and hence any desired damper opening.

At each of the short posts 45 adjacent the mounting of the power gear train there is a well 110 formed in the stationary structure of the ventilator immediately below the rectangular opening 54 in the damper. Such well has a bot-

tom plate 111 supported on the section 12 of the cross braces 11. Such plate if desired may extend across and rest on the shoulders 15. Vertical end walls 112 and side walls 113 define the well structure and these walls form supports or contact elements for the portions of the damper top 51 adjacent the opening 54. The purpose of having this opening 54 in the damper and the well is to permit the drop chains 91 and 93 for operating the pulley at the top to be brought into convenient position for operating. Therefore the bottom plate 111 is provided with a pair of openings 114 with a welded ring 115 adjacent the rim of each opening, this ring giving a positive edge, therefore the damper can be raised and lowered without the chains interfering with the motion of the damper.

At the ends of the damper one of the long posts 40 has a secondary well 120. This is formed by a panel plate 121 at the bottom secured to the cross member 12 of the braces 11 and may if desired be supported at the outside by the shoulders 15. End transverse vertical walls 122 extend across the full width of the damper opening terminating at the vertical rims 16. The portions of the damper adjacent the end thus each rest on the transverse end walls 122. It will be seen that there is therefore a slight space between two adjacent dampers at the end. As each shaft 66 is intended to at least control and open one damper, these shafts terminate as indicated at 125 on a journal 43, thus two adjacent shafts are supported in journals at their ends by the post extending upwardly from the well 120. The shafts are also supported at all of the intermediate posts 40, there being a sufficient number of these depending upon the necessary strength and rigidity required. As above mentioned, the sleeves 55 slide on the posts 40. They restrain the damper from tilting and also when the damper is in its lowermost position fit over any lock nuts or the like used in connection with these posts. The damper may be elevated until the necks contact the head 42 at the upper end of the posts 40.

As above mentioned, our invention also includes the equipment for closing the individual dampers or series of dampers in case of fire. Such equipment designated by the assembly numeral 150 includes a metal chain 151 having a series of fusible links one of which is indicated at 152 with one end of the chain connected by a strap 153 to a fixed structure. In the illustration this is attached to the lower end of one of the posts and preferably the post at the remote end of the damper where the equipment is to operate only one damper. The other end of the chain is attached to a fixed structure in a similar or other suitable manner. The chain passes through an eye 154 in a bracket 155 which is illustrated as connected to the lower end of the post 45 which forms the support and mounting for the pulley and gear drive equipment for the longitudinal shaft 66. A hook 156 fits loosely over the chain 151 and has a bolt 157 connected thereto with an assembly of weights 158 attached to the bolt. This allows building up of the total weight desired. Such assembly of weights has a perforation 159 extending vertically completely through the single or all of the weights of the assembly and through such perforation is fed the drop line of the drop chain 91, the large links 92 being below the weight. These links are of such diameter that they cannot pass through or enter the perforation 159, hence when the damper is raised, the drop

section 91 rises as the counterweight 94 moves downwardly but there is always a considerable distance between the links 92 and the weight 158. Hence, if any one of the fusible links 152 melts or fuses due to rise in temperature occasioned for instance by a fire, such link yields and thus destroys the supporting action and function of the chain 151. This gives sufficient looseness to the chain so that it may readily pull through the eye 154 if necessary and allows the weight 158 to suddenly drop. This strikes the large links 92 and rides downwardly on the drop section 91. The weight with its momentum is sufficient to overcome the reaction of the counterbalance weight 94 and start and continue the rotation of the chain pulley so that the shaft 66 rotates in the proper direction to unwind the cables allowing the damper to descend to the closed ventilator position.

Various changes may be made in the details of the construction without departing from the spirit or scope of the invention as defined by the appended claims.

We claim:

1. A continuous ventilator including a stationary ventilator structure of a roof having an elongated upwardly facing ventilator opening combined with a damper shaped to fit the opening and when resting on the ventilator structure form a closure, a shaft extending longitudinally above the damper substantially the full length of said damper and mounted for rotation on the fixed part of the ventilator construction, a remote control means for rotating the shaft, a series of cables each connected to the shaft and each to the damper at spaced intervals longitudinally of the shaft and damper and alternately on opposite sides of the damper whereby a rotation of the shaft and the winding of the cables on and off the shaft raises and lowers the damper.

2. A continuous ventilator in which a roof structure is provided with an upwardly facing ventilator opening combined with an elongated damper shaped to fit over said opening and when lowered to form a closure therewith, a rotatable shaft positioned above the axial center of the damper, a plurality of cables each connected to the shaft and spaced longitudinally thereof, the opposite end of each cable having a single connection to the damper, the connections of the plurality of the cables to the damper being alternately on opposite sides of such damper and longitudinally thereof, means to rotate the shaft for winding the cable thereon or releasing the cable from the shaft to thereby raise or lower the damper relative to the ventilator opening.

3. A continuous ventilator in which a roof structure is provided with an upwardly facing ventilator opening combined with an elongated damper shaped to fit over said opening and when lowered to form a closure therewith, a rotatable shaft positioned above the axial center of the damper, a plurality of cables each connected to the shaft and spaced longitudinally thereof, the opposite end of each cable having a single connection to the damper, the connections of the plurality of cables to the damper being alternately on opposite sides of such damper and longitudinally thereof, means to rotate the shaft for winding the cable thereon or releasing the cable from the shaft to thereby raise or lower the damper relative to the ventilator opening, a fire release mechanism including a weight, means to suspend such weight including a fusible member

releasing at a predetermined temperature and means actuated by the movement of the weight to operate the shaft rotating means to rotate such shaft in a direction to lower the damper.

4. A continuous ventilator including a stationary ventilator structure of a roof having an elongated upwardly facing ventilator opening combined with a damper shaped to fit the opening and when resting on the ventilator structure forming a closure, a shaft extending longitudinally above the damper and mounted for rotation on a fixed part of the ventilator structure, a series of cables connected to the shaft and to the damper and spaced longitudinally of the shaft and damper and connecting to opposite sides of the axial center of the damper and means to rotate the shaft to wind the cables on and off such shaft for raising and lowering the damper.

5. A continuous ventilator including a stationary ventilator structure of a roof having an elongated upwardly facing ventilator opening combined with a damper shaped to fit the opening and when resting on the ventilator structure forming a closure, a shaft extending longitudinally above the damper and mounted for rotation on a fixed part of the ventilator structure, a series of cables connected to the shaft and to the damper and spaced longitudinally of the shaft and damper and connecting to opposite sides of the axial center of the damper, a chain pulley and gear connection to the shaft with a drop chain extending below the damper and means on the drop chain to counterbalance the weight of the damper.

6. A continuous ventilator in which a roof structure is provided with an upwardly facing ventilator opening combined with a central well with perforations for a chain in the bottom thereof, a damper extending longitudinally of the upwardly facing opening, said damper having an opening registering with the well, a shaft above the damper, flexible means for interconnecting the shaft and the damper to raise and lower the damper on rotation of the shaft, a rotation means for the shaft including a chain pulley having drop chains extending downwardly through the opening in the damper and the perforations in the bottom of the well.

7. A continuous ventilator in which a roof structure is provided with an upwardly facing ventilator opening combined with an elongated damper shaped to fit over said opening and when lowered to form a closure therewith, a series of vertical posts extending upwardly from the said roof structure, a shaft journalled in the upper end of said posts, a series of cables attached to the shaft and connected to the damper and positioned longitudinally thereof and means to rotate the shaft whereby the damper is raised and lowered.

8. A continuous ventilator in which a roof structure is provided with an upwardly facing ventilator opening combined with an elongated damper shaped to fit over said opening and when lowered to form a closure therewith, a

series of vertical posts extending upwardly from the said roof structure, a shaft journalled in the upper end of said posts, a series of cables attached to the shaft and connected to the damper and positioned longitudinally thereof and means to rotate the shaft whereby the damper is raised and lowered, the damper having openings with sleeves, the posts extending through the opening and sleeves and the sleeves forming a guide on the post for the damper.

9. A continuous ventilator in which a roof structure is provided with an upwardly facing ventilator opening combined with an elongated damper shaped to rest upon the roof structure at the ventilator opening and form a closure therefor, a rotatable shaft positioned above the damper and extending substantially the full length of said damper, a series of single cables each connected to the damper and attached to said shaft at spaced intervals and alternately on opposite sides of the damper for winding on and off the shaft to thereby raise and lower the damper, and means for rotating said shaft.

10. A continuous ventilator including a stationary ventilator structure of a roof having an elongated upwardly facing ventilator opening combined with a damper shaped to fit the opening and when resting on the ventilator structure forming a closure, a shaft extending longitudinally above the damper and mounted for rotation on a fixed part of the ventilator structure, a series of cables connected to the shaft and to the damper and spaced longitudinally of the shaft and damper and connecting to opposite sides of the axial center of the damper, a pulley operatively connected to the shaft and having a chain operating thereover with at least one drop end, a weight having a guide means through which the drop end of the chain passes, the chain in rotating the pulley rotating the shaft to wind the cables on and off the shaft for raising and lowering the damper, a support for the weight independent of and entirely separate from the said chain and having a fusible suspension means whereby on fusing of the fusible means the weight may drop and means to interengage the weight with the drop end of the chain to rotate the pulley and hence the shaft for closing the damper.

11. In a device as described having a shaft with a mechanism operated thereby on rotation of the shaft, a pulley having a drive connection for the shaft, a chain operating over the pulley and having at least one drop end, a weight provided with a guide means through which the said drop end of the chain extends, a suspension device for the weight including a flexible means separate and distinct from the said chain and a fusible connection with a fixed support whereby on the fusing of the fusible means the said weight is released to drop and means to interengage the weight with the said drop end of the chain for rotating the pulley and hence the shaft.

ABRAHAM HERMAN.
JOSEPH HERMAN.
